UNITED STATES PATENT OFFICE.

JAMES COCHRANE HUTTON, OF BIRMINGHAM, ENGLAND, ASSIGNOR TO THE BRITISH LIGHTING AND IGNITION COMPANY LIMITED, OF BIRMINGHAM, ENGLAND, A BRITISH COMPANY. DYNAMO-ELECTRIC MACHINE.

Application filed January 22, 1926, Serial No. 82,897, and in Great Britain May 16, 1924.

This invention relates to dynamo electric machines and has special reference to ignition magnetos of the type in which the armature is fixed and there is employed in conjunction therewith a rotary unwound permanent magnet or rotary unwound inductors and stationary magnets.

The object of the present invention is to provide improved means for obtaining automatic or hand adjustment of the timing position of magnetos of the kind above referred to. For this purpose according to the present invention the rotating magnet system or inductors of the magneto and the high tension distributor drive mechanism are mounted directly on a sleeve rotatably mounted on the driving shaft of the magneto and the contact breaker or cam is mounted on the spindle of the high tension distributor or on the said sleeve whereby hand control or automatic control of the timing of the spark can be effected by relative angular displacement between the sleeve and the shaft. The automatic adjustment of the relative positions of the sleeve and the driving shaft is preferably obtained by means of a centrifugally acting device connected with the said shaft or sleeve and driven directly from the driving shaft. For effecting hand control of the timing of the spark the rotating magnet system or inductors of the magneto are mounted on a sleeve rotatably mounted on the driving shaft of the magneto, and the driving shaft is either made hollow and the required displacement is obtained by means of a pin operating through the hollow driving shaft, or there may be mounted on the driving shaft a slideable sleeve carrying a pin adapted to engage with a suitably arranged slot in a hub rotatably mounted on the shaft.

In order that the invention may be clearly understood and readily carried into effect, the same will now be described more fully with reference to the accompanying drawings, in which:

Figure 1 illustrates a magneto provided with means for obtaining automatic or hand operated control of the timing of the spark, 50 Figure 2 is a transverse section on the line 2-2 of Figure 3,

Fig. 3 is an enlarged sectional view of operating parts of the automatic and hand spark adjusting mechanism, and

Figure 4 is a detail view of a modified 55 construction in which the contact breaker or cam is mounted on the sleeve instead of on the spindle of the high tension distributor as in Figure 1.

Referring to the drawings the rotatable 60 magnet or inductors 2 of the magneto and the gear drive 5 to the high tension distributor 26 are mounted on a sleeve 11 which is rotatably mounted upon the driving shaft 14 supported in bearings 7. The contact 65 breaker or cam 6 is mounted on the spindle 25 of the high tension distributor 26 as shown in Figure 1 or on the sleeve 11 as shown in Figure 4. The shaft 14 is made hollow so as to receive a shaft 17 which is 70 movable longitudinally from the outside of the machine; the shaft 17 carries at one end a pin 18 which engages an obliquely cut slot 27 in the shaft 14 and with an oppositely cut slot 28 in the rotatable hub 19, so that 75 movement of the pin 18 in an endwise or axial direction causes a rotation of the hub 19. The hub also carries lugs 20^a to which links 21 are fastened through pins 20 at one end, the other ends of the links being attached to weights 22 which in turn are connected through links 23 to the rotor 2 to which the said links are pivoted by the pins 24. It will be seen therefore that by an endwise movement of the shaft 17 angular displacement of the pin 24 is obtained and a further movement is obtained by radial displacement of the weights 22 by centrifugal force, which tends to draw the pins 20 and 24 closer together. By the angular movement of 80 the sleeve 11 they may be effected either manually or automatically as above described on the occurrence of a variation in the speed of the rotor the timing of the spark is adjusted with regard to the position of the engine shaft, and the opening of the contact points takes place at the same position of the rotor with regard to the stator, thereby ensuring the maximum efficiency of the magneto at all timing positions.

It is to be understood that the means hereinbefore described for obtaining the automatic or hand adjustment of the timing position of a magneto are of course also applicable to magnetos when arranged with 85 a dynamo in a combined unit as described and claimed in the specification of my co-pending application Serial No. 31,319 filed 100 105

May 19, 1925 but that no claim is made in the present specification to a combined unit in which the magneto is provided with the improved means in question, such combined 5 unit including a magneto provided with the said means for controlling the timing of the spark being claimed in my aforesaid specification Serial No. 31,319.

What I claim and desire to secure by Letters Patent of the United States is:—

1. An ignition magneto of the kind referred to comprising a fixed armature and a rotary permanent magnet system, a driving shaft for the rotary magnet system, bearings for supporting said driving shaft, a sleeve rotatably mounted on said driving shaft, said rotary magnet system being mounted directly on said sleeve, a high tension distributor drive mechanism mounted 10 directly on said sleeve, a contact breaker, means for actuating said contact breaker from said sleeve, said sleeve with the members aforementioned mounted thereon being located between the bearings of the driving 15 shaft, and a centrifugally acting means comprising a hub mounted on said shaft and weights connected through one set of links to the hub and through another set of links to the rotary magnet system for effecting 20 relative angular displacement between the hub and the shaft for controlling the timing 25 of the spark.

2. An ignition magneto of the kind referred to comprising a fixed armature and 30 a rotary permanent magnet system, a driving shaft for the rotary magnet system, bearings for supporting said driving shaft, a sleeve rotatably mounted on said driving shaft, said rotary magnet system being mounted directly on said sleeve, a high tension distributor, said high tension distributor being provided with a spindle, mechanism for driving said high tension distributor mounted directly on said sleeve, a contact breaker mounted on said spindle, said sleeve with the members aforementioned mounted thereon being located between the bearings of the driving shaft, and a centrifugally acting means comprising a hub 35 mounted on said shaft and weights connected through one set of links to the hub and through another set of links to the rotary magnet system for effecting relative angular displacement between the sleeve and the shaft for controlling the timing of the spark.

3. An ignition magneto of the kind referred to comprising a fixed armature and a rotary permanent magnet system, a hollow driving shaft for the rotary magnet system, bearings for supporting said driving shaft, a sleeve rotatably mounted on said driving shaft, said rotary magnet system being mounted directly on said sleeve, a high tension distributor drive mechanism mounted directly 60 on said sleeve, a contact breaker, means for actuating said contact breaker from said sleeve, said sleeve with the members aforementioned mounted there-

actuating said contact breaker from said sleeve, said sleeve with the members aforementioned mounted thereon being located between the bearings of the driving shaft, a hub mounted on the driving shaft, a centrifugally acting device connected with the said hub and sleeve, and a solid shaft carrying a pin, said solid shaft being longitudinally movable within the hollow driving shaft, said hollow driving shaft being provided with an elongated slot cut at an angle to the axis and said hub being provided with an elongated slot cut at an angle to the axis opposite to that of the slot formed in the hollow driving shaft, and said pin carried by the solid shaft engaging with the slots in the driving shaft and hub so that axial movement of the solid shaft and the pin carried thereby imparts angular movement to the hub.

4. An ignition magneto of the kind referred to comprising a fixed armature and a rotary permanent magnet system, a hollow driving shaft for the rotary magnet system, bearings for supporting said driving shaft, a sleeve rotatably mounted on said driving shaft, said rotary magnet system being mounted directly on said sleeve, a high tension distributor, said high tension distributor being provided with a spindle, mechanism for driving said high tension distributor mounted directly on said sleeve, a contact breaker mounted on said spindle, said sleeve with the members aforementioned mounted thereon being located between the bearings of the driving shaft, a hub mounted on the driving shaft, a centrifugally acting device connected with the said hub and sleeve, and a solid shaft carrying a pin, said solid shaft being longitudinally movable within the hollow driving shaft, said hollow driving shaft being provided with an elongated slot cut at an angle to the axis and said hub being provided with an elongated slot cut at an angle to the axis opposite to that of the slot formed in the hollow driving shaft, and said pin carried by the solid shaft engaging with the slots in the driving shaft and hub so that axial movement of the solid shaft and the pin carried thereby imparts angular movement to the hub.

5. An ignition magneto of the kind referred to comprising a fixed armature and a rotary permanent magnet system, a hollow driving shaft for the rotary magnet system, bearings for supporting said driving shaft, a sleeve rotatably mounted on said driving shaft, said rotary magnet system being mounted directly on said sleeve, a high tension distributor drive mechanism mounted directly on said sleeve, a contact breaker, means for actuating said contact breaker from said sleeve, said sleeve with the members aforementioned mounted there-

on being located between the bearings of the drive shaft, a centrifugally acting means comprising a hub mounted on said shaft and weights connected through one set of links to the hub and through another set of links to the rotary magnet system, and a solid shaft carrying a pin, said solid shaft being longitudinally movable within the hollow driving shaft, said hollow driving shaft being provided with an elongated slot cut at an angle to the axis and said hub being provided with an elongated slot cut at an angle to the axis opposite to that of the slot formed in the hollow driving shaft, and said pin carried by the solid shaft engaging with the slots in the driving shaft and hub so that axial movement of the solid shaft and the pin carried thereby imparts angular movement to the hub.

6. An ignition magneto of the kind referred to comprising a fixed armature and a rotary flux distributor, a driving shaft for the rotary flux distributor, bearings for supporting said driving shaft, a sleeve rotatably mounted on said driving shaft, said rotary flux distributor being mounted directly on said sleeve, a high tension distributor drive mechanism mounted directly on said sleeve, a contact breaker, means for actuating said contact breaker from said sleeve, said sleeve with the members aforementioned mounted thereon being located between the bearings of the driving shaft, a hub mounted on the driving shaft, and means comprising a centrifugally acting device connected with the said hub and sleeve for effecting relative angular displacement between the sleeve and the shaft for controlling the timing of the spark.

7. An ignition magneto of the kind referred to comprising a fixed armature and a rotary flux distributor, a driving shaft for the rotary flux distributor, bearings for supporting said driving shaft, a sleeve rotatably mounted on said driving shaft, said rotary flux distributor being mounted directly on said sleeve, a high tension distributor drive mechanism mounted directly on said sleeve, a contact breaker, means for actuating said contact breaker from said sleeve, said sleeve with the members aforementioned mounted thereon being located between the bearings of the driving shaft, a hub mounted on the driving shaft, and a solid shaft carrying a pin, said solid shaft being longitudinally movable within the hollow driving shaft, said hollow driving shaft being provided with an elongated slot cut at an angle to the axis and said hub being provided with an elongated slot cut at an angle to the axis opposite to that of the slot formed in the hollow driving shaft, and said pin carried by the solid shaft engaging with the slots in the driving shaft and hub so that axial movement of the solid shaft and the pin carried thereby imparts angular movement to the hub.

JAMES COCHRANE HUTTON.
